UNITED STATES PATENT OFFICE

2,129,808

BLOWER

Oliver D. H. Bentley, Norfolk, Mass.

Application November 9, 1937, Serial No. 173,637

4 Claims. (Cl. 230—116)

This invention relates to blowers and relates more particularly to a combined propeller and centrifugal blower.

For some classes of work such for example, as providing air for forced draft for naval vessels, air pressures of the order of 16" of water are required. In order to provide such pressures in the past, it has been the practice to rotate the blower blades at such high speeds that they were not only very noisy in operation but the strains to which they were subjected were great.

According to this invention, a propeller type fan rotating in one direction at a reduced speed, feeds air axially into the inlet of the wheel, rotating in the opposite direction at a reduced speed, of a centrifugal fan. This results in energy conversion at high efficiency and provides the desired air pressure at greatly reduced speed.

In one embodiment of the invention, a propeller type fan is mounted in the inlet of a centrifugal fan. Oppositely revolving rotors of a steam turbine drive the propeller blades and the fan wheel through concentric shafts. The high relative speeds of the turbine rotors result in an efficient prime mover, while providing the reduced speed desired for the fan rotors. The propeller blades act to "super-charge" the centrifugal fan, the air from which is discharged through a preferred involute casing.

An object of the invention is to provide relatively high air pressures by means of relatively low speed blowers.

Another object of the invention is to super-charge a centrifugal fan with a propeller fan.

Another object of the invention is to super-charge a centrifugal fan with a propeller rotating in a direction opposite to that of the fan wheel.

Another object of the invention is to rotate a propeller fan located in the inlet of a centrifugal fan from one rotor of a prime mover while rotating the fan wheel of the centrifugal fan from another rotor of the prime mover, revolving in a direction opposite to that of the first mentioned rotor.

Other objects of the invention will be apparent from the following description taken together with the drawings.

The invention will now be described with reference to the drawings, of which:

Fig. 1 is a side elevation of one embodiment of this invention;

Fig. 2 is a sectional view along the lines 2—2 of Fig. 3;

Fig. 3 is an enlarged cross-section of Fig. 1, and

Fig. 4 is an enlarged section along the lines 4—4 of Fig. 3.

The propeller blades 10 on the hub 11 are mounted in the inlet passage 12 upon the solid shaft 13. The centrifugal fan wheel 14 with blades 15 is mounted upon the hollow shaft 16. The solid shaft 13 revolves within the hollow shaft 16. The hollow shaft 16 is attached to the rotor 18 of the steam turbine indicated generally by 19, and the solid shaft 13 is attached to the rotor 20 of the turbine. The wheel 14 and rotor 18 rotate around the ball bearings 17 which are supported by the vertical extension 30 of the casing 28 of the turbine 19. The details of the turbine rotors and their cooperating mechanism 15 are similar to those disclosed in my Patent No. 1,434,672, issued Nov. 7, 1922, and will not be described in detail here.

In the embodiment of the invention illustrated by the drawings, the upper end of the shaft 13 is supported by the thrust bearing 21 which is enclosed in and supported by the stream-lined hub 22. The hub 22 is supported from the wall 23 by means of the arms 24.

The casing 25 of the centrifugal fan is supported from the wall 23 as by the bolts 26 in the horizontal extension 27. The casing 28 of the turbine 19 is supported from the lower portion of the casing 25 by means of the bolts 29.

To prevent the passage of steam from the turbine 19 between the inner shaft 13 and the outer shaft 16, the shaft 13 has attached to it just above the uppermost bearing 17, the member 30 which forms a basin containing the mercury 31. Attached to the upper portion of the hub of the fan wheel 14 is the member 32 which has a portion 33 which extends downwardly into the mercury 31, forming with the mercury, the shaft 13 and the member 30, a mercury seal which prevents steam leakage between the shafts.

In operation, the rotors 18 and 20 of the turbine 19 revolve in opposite directions. The linear velocities of the rotors are relatively low but their relative velocity is relatively high resulting in high turbine efficiency. The rotor 18 revolves the shaft 16 and centrifugal fan wheel in one direction while the rotor 20 revolves the shaft 13 and the propeller blades 10 in the opposite direction. The propeller blades 10 deliver a high velocity, whirling air stream, axially into the inlet of the centrifugal fan wheel 14. The blades 15 of the wheel 14 revolving in opposite direction to that of the whirling air stream delivered by the propeller blades 10, impact it at high relative velocity providing high energy conversion and a

relatively high air pressure. The air under high pressure is delivered at the outlet 34 of the involute casing 25 to be used as desired.

The inlet passage 12 need not, of course, be an opening in a wall as in the embodiment illustrated. The passage may be provided by a casing as is usual in the art. Likewise the centrifugal fan blades may be curved instead of radial as shown, and other departures may be made by those skilled in the art without departing from the spirit of the invention.

What is claimed is:

1. A blower assembly comprising in combination, a centrifugal fan wheel, means forming an axial air inlet passage into the eye of said wheel, propeller blades in said passage, a steam turbine having rotors adapted to turn in opposite directions, means connecting one of said rotors with said propeller blades, and means connecting the other of said rotors with said wheel.

2. A blower assembly comprising in combination, a centrifugal fan wheel, a fan casing for collecting and discharging the air from said wheel, means forming an axial air inlet passage into the eye of said wheel, propeller blades in said passage, a pair of concentric shafts, means for supporting said wheel on one of said shafts, means for supporting said blades upon the other of said shafts, a steam turbine having rotors adapted to turn in opposite directions, means for attaching one of said rotors to one of said shafts, and means for attaching the other of said rotors to the other of said shafts.

3. A blower assembly comprising in combination, a centrifugal fan wheel, a fan casing for collecting and discharging the air from said wheel, means forming an axial air inlet passage into the eye of said wheel, propeller blades in said passage, a pair of concentric shafts, means for supporting said wheel on one of said shafts, means for supporting said blades upon the other of said shafts, a steam turbine having rotors adapted to turn in opposite directions, means for attaching one of said rotors to one of said shafts, means for attaching the other of said rotors to the other of said shafts, a turbine casing enclosing said rotors, and means for supporting said turbine casing from said fan casing.

4. A blower assembly comprising in combination, a centrifugal fan wheel, a fan casing for collecting and discharging the air from said wheel, means forming an axial air inlet passage into the eye of said wheel, propeller blades in said passage, a pair of concentric shafts, means for supporting said wheel on the outer of said shafts, means for supporting said blades upon the inner of said shafts, a steam turbine having rotors adapted to turn in opposite directions, means for attaching one of said rotors to one of said shafts, means for attaching the other of said rotors to the other of said shafts, and means forming a mercury seal between said wheel and the inner of said shafts.
